J. Ledermann

ATTORNEY

UNITED STATES PATENT OFFICE.

LEON PIERCE, OF NEW YORK, N. Y.

BUILDING PILE.

REISSUED

Application filed June 2, 1927. Serial No. 195,896.

The main object of this invention is to provide a novel type of pile used in constructing the foundations of buildings, and consists of three sections, a soil penetrator nose, 5 a hole forming sleeve and a series of inner shells, open at both ends into which the cement is poured after the outer hole forming sleeve has been removed or salvaged.

Another object of this invention is to provide a pile used in the construction of all kinds of buildings which consists of three sections, a penetrator nose, and an inner and outer shell, the inner shell being composed of sections which are adapted to be filled 10 with concrete while the outer shell is adapted to be extracted and salvaged.

The above and other objects will become apparent in the description below in which characters of reference refer to like-named 15 parts in the drawing.

Referring briefly to the drawing, Figure 1 is a longitudinal sectional elevational view of the pile showing the same in its entirety.

Figure 2 is a reduced front elevational 20 view showing the pile being sunk into the ground with the aid of a steam hammer.

Figure 3 is a longitudinal sectional elevational view of the pile similar to Figure 1 but showing the outer sleeve partly extracted. 25

Figure 4 is a cross sectional view of the pile, the section being taken on line 4—4 of Figure 1.

Referring in detail to the drawing, the 30 numeral 10 indicates a conical tapering penetrator nose which is of substantial construction so that it may withstand fracture when coming into contact with stone or other similar hard substance found in the soil. This 35 nose is of hollow construction having an inverted conical chamber 11. A rib 12 extends upwardly and diametrically from the apex of the chamber and this rib is provided with an opening 13 which passes entirely thru it 40 from one side to the other. The tip of the nose always hangs in suspended position and is the first to enter or pierce the soil. The upper open portion of the nose is encircled by a flat shoulder 14 which is surmounted 45 by an internal annular rim 15.

The lower end of an outer shell 16 is seated 50 on the shoulder 14 in contact with the rim 15 which latter serves as a positioning member for the outer shell. This shell is of the 55 same length as the distance the pile is to be sunk and is formed of a unitary piece of ma-

terial of seamless construction. The upper end of the outer shell is provided with a plurality of openings 17 into which tackle is inserted when the shell is to be extracted from 60 the well it has formed.

A plurality of hollow sleeves 18 open at both ends, and of a dimension smaller than the outer shell are slipped into the outer shell after the latter has been sunk to the 65 desired position. The lower ends 20 of these sleeves are formed with a reduced diameter so that the reduced end of one sleeve telescopes partly into the larger end of the sleeve above it. Each sleeve is provided with a 70 series of perforations 19 which are provided at spaced apart positions around the circumference thereof.

The opening 13 on the rib 12 of the penetrator nose receives the lower looped end 24 75 of a tie rod 21. The tie rod extends axially upward within the sleeves and projects from the upper end of the uppermost sleeve, and the end of the tie rod projecting therefrom is threaded and is adapted to be engaged by 80 a pair of nuts 23. The latter retain an annular face plate 22 in position on the uppermost sleeve. This face plate has an axial opening therein in which the upper end of the tie rod registers.

The construction of the pile is such that the outer shell 16 is salvaged and may be used over and over again until it is worn out or damaged. The outer shell 16 and the nose 10 are secured to each other thru a friction fit, the nose hanging suspended as shown in Figure 2 from the outer shell. This shell and nose are guided into position between the leads 25 of a pile driver. In sinking the pile a steam hammer 26 is seated on the upper end of the outer shell 16 and operation of the hammer causes the nose to penetrate the soil and thereby sink the nose and the outer shell to the desired depth. Before the outer shell 16 is withdrawn from the well which 90 has been formed by the nose, the sleeve sections 18 are inserted into the outer shell one after the adjacent one by slipping the lower reduced end of one section into the larger end of the next lowest section. The sleeves 95 are very apt to cling to the outer shell surface and thereby be raised with the outer shell as the latter is being extracted from the well. To prevent the sleeves from being removed from the interior of the outer shell, the face plate 22 is secured in place by passing 100 the upper end of the tie rod, which is thread-

110

ed, thru the axial opening provided in the face plate and then securing the nuts 23 in place in the manner illustrated in Figure 1. After the outer shell 16 has been extracted 5 from the well an annular void exists between the outer surface of the sleeve sections and the surface of the well. After partly or wholly removing the face plate from the uppermost sleeve, cement is dumped into 10 the sleeve until the pile form has been filled with cement which is poured in thru the uppermost sleeve situated at the upper end of the construction. The cement seeps thru the perforations 19 which are formed near 15 the upper end of each sleeve section and that cement which passes thru these perforations drops into the space between the sleeves and the wall of the well and fills this void so that both sides of the sleeves will be covered 20 by a coating of cement.

It is to be noted that certain changes in form and construction may be made without departing from the spirit and scope of the invention.

25 I claim:

1. In a building pile, a conical hollow nose, an outer removable shell seated on said nose, sleeves in said shell slipping end to end one into the other, and means engaging 30 said nose and the uppermost sleeve for securing the sleeves in place while extracting said shell.

2. In a building pile, a conical hollow nose having its apex in suspended position, 35 an outer removable shell seated on said nose and frictionally secured thereto, a plurality of sleeves open at both ends secured to each other end to end, the lowermost sleeve seat-

ing on the nose, and means engaging the nose and the uppermost sleeve for retaining 40 the sleeves in arranged formation while the shell is being removed.

3. In a building pile, a conical hollow nose having a shoulder thereon, an internal encircling rim on said nose, an outer shell having its lower end seated on said shoulder in contact with the encircling rim, a plurality of sleeves connected end to end adapted to be slipped into said shell after the ground has been pierced, the lowermost sleeve seating 50 on the rim of said nose, said nose having a diametral rib formed therein, said rib having an opening, and means engaging in the opening in the rib and the uppermost sleeve for securely retaining the sleeves intact with the nose while the outer sleeve is being extracted.

4. In a building pile, a conical hollow nose having a shoulder thereon, an internal encircling rim on said nose, an outer shell having its lower end seated on said shoulder and in contact with the encircling rim, a rib extending upwardly in said nose having an opening therein, a plurality of sleeves secured to each other end to end and having perforations therein, the lowermost sleeve being seated on the rim of said nose, a face plate seated on the uppermost sleeve, a tie rod engaged in the opening of said rib extending axially upward having a threaded upper end, and nuts engaging the threaded end for securing the face plate in seated position on the uppermost sleeve to retain the sleeves mounted on the nose.

In testimony whereof I affix my signature.
LEON PIERCE.
